[57] CLAIM

The ornamental design for a container lid, as shown and
described.

DESCRIPTION

FIG. 1 is a front perspective of a container lid, showing
my new design;

FIG. 2 is a top plan thereof;

FIG. 3 is a bottom plan thereof;
FIG. 4 is a side view thereof, the opposite side being the
same in appearance; and

FIG. 5 is a rear view thereof.

FIG. 1

FIG. 2

FIG. 3

FIG. 4
